[57] CLAIM

The ornamental design for a bore-aligning tool, substantially as shown.

DESCRIPTION

FIG. 1 is a perspective view of a bore-aligning tool showing my new design;

FIG. 2 is a side elevational view on a slightly larger scale looking at the side of the tool opposite that shown in FIG. 1;

FIG. 3 is an end elevational view looking toward the left hand end of the tool as viewed in FIG. 2; and FIG. 4 is a similar view looking toward the opposite end of the bore-aligning tool.
